SPECTACLE CASES

Joseph A. Hueber, Narberth, and Edward K. Hueber, Philadelphia, Pa., assignors to Kelley & Hueber, Inc., Philadelphia, Pa., a corporation of Pennsylvania

Filed Jan. 30, 1958, Ser. No. 712,607

4 Claims. (Cl. 206—5)

This invention relates to improvements in spectacle cases, and more particularly concerns spectacle cases having means for spacing the spectacle lenses from the walls of the cases.

This application comprises a continuation-in-part of our previous United States patent application Serial No. 652,590, filed April 12, 1957, for a spectacle case, now abandoned.

In designing spectacle cases, special attention has been given to the problem of preventing scratching or otherwise marring of the lenses of the spectacles. Because spectacle lenses are made from relatively soft glass, they are more susceptible to such damage than are ordinary glass objects. In the past, designers have sought to overcome the problem of lens scratching by lining the inner walls of spectacle cases with soft materials such as leather, velveteen, silk and the like. Such linings are intended to provide a soft surface against which the lenses rest in the case.

Inner case linings have not proven to be fully satisfactory for the reason that in the course of use of the cases dirt, grit and similar foreign matter tend to collect and become embedded in the linings. Since the lenses of the spectacles in such cases rest snugly against the wall lining, they are often pressed against such embedded foreign matter and become scratched or otherwise damaged. The recent and rapidly growing use of plastic lenses, which are considerably softer than glass lenses, and hence more susceptible to damage, has made the problem of lens protection more acute.

The chief aim of this invention is to overcome the above described disadvantages by providing spectacle cases having means for spacing the lenses of the spectacles between and free of contact with the walls of the cases, and thereby prevent the lenses from rubbing or being pressed against the surfaces of the walls with resultant likelihood of scratching, marring or other damage.

Other objects and advantages of this invention will be obvious from the following detailed description of the attached drawings, wherein:

Fig. 1 is a view in front elevation of a preferred spectacle case embodying this invention and having a pair of spectacles therein;

Fig. 2 is a view in front elevation of a plastic liner for use in the case of Fig. 1;

Fig. 3 is a view in top plan of the case liner shown in Fig. 2;

Fig. 4 is a view in section taken as indicated by the angled arrows IV—IV in Fig. 2;

Fig. 5 is an enlarged, partial view of the right hand end of the liner of Fig. 3;

Fig. 6 is a partial view in section taken as indicated by the angled arrows VI—VI in Fig. 5;

Fig. 7 is a view in section taken as indicated by the angled arrows VII—VII in Fig. 1;

Fig. 8 is a view in front elevation of another type of spectacle case embodying this invention and having a pair of spectacles therein;

2

Fig. 9 is a partial view in section taken as indicated by the angled arrows IX—IX in Fig. 8;

Fig. 10 is a perspective view of the nose block and lens spacing means of the case of Fig. 8, the two elements being disengaged;

Fig. 11 is a fragmentary view in perspective showing the nose block and lens spacing means of Fig. 10 as an integral unit;

Fig. 12 is a perspective view of a nose block and a modified lens spacing means for use in the case of Fig. 8, the two elements being disengaged;

Fig. 13 is a perspective view showing the nose block and lens spacing means of Fig. 12 in assembled relation;

Fig. 14 is a view similar to Fig. 9 showing use of the nose block and lens spacing means of Figs. 12 and 13 in the case of Fig. 8;

Fig. 15 is a perspective view showing the nose block and lens spacing means of Figs. 12 and 13 as an integral unit;

Fig. 16 is a perspective view of another modified integral nose block and lens spacing means with a pair of spectacles supported thereon;

Fig. 17 is a partial view in section taken as indicated by the angled arrows XVII—XVII in Fig. 16 showing the nose block and lens spacing means thereof inserted in a spectacle case;

Fig. 18 is a perspective view of yet another modified integral nose block and lens spacing means with a pair of spectacles supported thereon;

Fig. 19 is a partial view in section taken as indicated by the angled arrows XIX—XIX in Fig. 18 showing the nose block and lens spacing means thereof inserted in a spectacle case;

Fig. 20 is a perspective view of yet another type of spectacle case embodying this invention and having a pair of spectacles therein; and

Fig. 21 is a sectional view taken as indicated by the angled arrows XXI—XXI in Fig. 20.

Although specific terms are used in the following description for clarity, these terms are intended to refer only to the structures shown in the drawings and are not intended to define or limit the scope of the invention.

Turning now to the specific embodiment of the invention selected for illustration in Figs. 1-7 of the drawings, the number 11 designates generally a spectacle case having a cuplike liner 15 inserted therein. Spectacle case 11 is preferably made of a flexible material, such as leather or plastic, and liner 15 is preferably made of a rigid material, such as plastic formed by the injection molding process. In practice, liners made of high impact styrene have proven to be highly satisfactory.

Referring particularly to Figs. 1 and 7, the spectacle case 11 is formed with opposing front and rear walls 16 and 17 of like contour and size which are joined together along their abutting bottom and side edges by suitable means, such as stitches 18, to form a pocket. It will be understood that walls 16 and 17 may be joined together by other means, such as by an adhesive, or by heat sealing, if made of plastic. Flap 13, which preferably is formed integrally with wall 17, is adapted to overlie the outside surface of wall 16 to provide a closure for the case 11. The walls 16 and 17 and flap 13 of case 11 are blanked from suitable sheet material in a manner well known in the art and are shaped so as to provide a pocket of suitable configuration for snugly retaining the liner 15. A snap fastener having female element 21 mounted in flap 13 and male element 22 mounted in wall 16 is used to detachably close the case 11.

As shown, the cuplike liner 15 is snugly fitted into the pocket formed by case walls 16 and 17. The liner 15 is of such configuration and dimension internally as

to securely retain a pair of spectacles therein while at the same time permitting their easy insertion and removal.

The spectacles 23 held in the liner 15 have lenses 26 and a frame 24 which includes temples 25, a nose bridge 27 and nose rest pieces 30. The lenses 26 face rearwardly of the case 11 and the temples 25 are folded over the outside surface of the front wall 16. Thus, the temples 25 are securely retained between the front wall 16 and the flap 13 when the case 11 is closed.

As shown in Figs. 2 and 3, the liner 15 is divided transversely into separate, opposing front and rear portions 28 and 29. The inner surface of rear portion 29 is provided with a lens spacer element 31 which has grooves 32 formed therein to effect a saving of material. Spacer element 31 contacts nose bridge 27 of the spectacles 23 to space the lenses 26 from the rear wall of liner 15. The nose rest pieces 30 of the spectacles 23 contact the front wall of the liner 15 and space the lenses 26 therefrom. Thus, the spectacle lenses 26 are spaced from both the front and rear walls of the liner 15 and are prevented from being scratched or otherwise damaged by reason of contact with the liner 15.

The liner rear portion 29 is of a height sufficient to provide full protection for the lenses 26 while the liner front portion 28 is of somewhat less height to enable the temples 25 to envelop the outside of front wall 16. The top edges 40 of the side walls of the liner 15 are forwardly inclined so as to merge with the top edges of the front and back walls thereof and thereby provide a smooth periphery about the open end of the liner. Rear portion 29 of the liner 15 (see Fig. 5) is provided at each side thereof with bosses 33 which have extending inwardly therefrom protuberances 34. Front portion 28 is similarly provided with bosses 35 which have formed therein recesses 36 for detachably and snugly engaging the protuberances 34. Rear portion 29 of liner 15 is further provided with centrally disposed inwardly extending protuberances 37 and 38 (see Fig. 4) which detachably and snugly engage, respectively, spuds 41 and 42 extending from the inner surface of front portion 28 of liner 15. Spud 41 also acts as a support member or nose block for nose bridge 27.

As may readily be seen, in assembling case liner 15, recesses 36 engage protuberances 34, recess 43 engages protuberance 37 and recess 44 engages protuberance 38 to detachably secure the front and rear portions 28 and 29 of case liner 15.

The outer surface of the front portion 28 of liner 15 may be provided with a protuberance 45 to fit snugly within the hollow 46 formed in the male member 22 of the snap fastener to retain the liner securely within the pocket of the case 11. Additionally, the outer surfaces of the liner portions 28 and 29 may be roughened or stippled to promote frictional resistance with the inside surfaces of pocket walls 16 and 17 and thereby aid in retaining the liner securely in the pocket of case 11.

Alternatively, the liner 15 may be firmly retained in the pocket of case 11 by means of an adhesive bond between the contiguous walls of the liner and case. When the liner 15 is composed of a plastic material, an effective bond for this purpose is achieved by applying a thin coating of a volatile plastic solvent to the outside walls of the liner prior to its insertion in the pocket of the case 11. The solvent acts to liquefy the outside surfaces of the liner 15 and the liquid plastic thereof coats the inside walls of the case 11. Upon evaporation of the solvent, the liquified plastic returns to its solid state and in so doing adheres to the inside walls of the case 11, thus creating a bond between the liner and the case pocket. With a liner 15 composed of styrene, a solvent presently distributed under the trademark "Lo-Tox Plastic Adhesive No. 5" by Globe Solvents Company, Inc. of Philadelphia, Pennsylvania, and comprising a mixture of acetone, methyl-ethyl-ketone and lacquer thinner, serves as an effective bonding solvent.

Referring now to Figs. 8 and 9, the spectacle case 51

there shown has front and rear walls 52 and 53 preferably integrally joined along a juncture 54. A flap 55 integrally joined to rear wall 53 is adapted to overlie the outside surface of front wall 52 to provide a closure for the case 51. The walls 52 and 53 and flap 55 are blanked from flexible sheet material to provide a case suitably configured to snugly retain a pair of spectacles having lenses 26, temples 25, a nose bridge 27 and nose rest pieces 30. As may readily be seen, the side edges of the walls 52 and 53 are not joined and hence the case 51 is open at both ends.

A snap fastener having male and female elements 57 and 58 is used to detachably close the case 51. Referring to Fig. 9, it will be seen that the male element 57 of the snap fastener is clamped to the front wall 52 of the case 51 by a pair of opposing flanges 69 and 70 disposed, respectively, on the outside and inside of wall 52 and joined by a sleeve or stud 71.

Disposed within the case 51 is a nose block 59 of generally U-shaped configuration and a lens spacer element 60 of generally rectangular configuration. As best shown in Fig. 10, the front end of the nose block 59 is formed with a partial wall 62 having a centrally disposed opening 63 therein of a generally keyhole-like configuration. The top portion of the opening 63 comprises a circular aperture 64 at the bottom of which are disposed a pair of spaced opposing protuberances 65. The rear side edges 66 of the opposing legs of the nose block 59 taper forwardly from the top thereof. The nose block 59 is formed of resilient material such as sheet metal suitably blanked, or plastic, such as styrene, suitably injection molded.

The spacer element 60 has a U-shaped groove 67 formed in its front face into which the rear portion of the nose block 59 is snugly engaged, as shown in Fig. 9. The spacer element 60 may be composed of either metal or plastic, but it is not necessary that it be of the same composition as the nose block 59. However, if desired, the nose block 59 and spacer element 60 may be formed as an integral unit, as shown in Fig. 11.

The nose block 59 and lens spacer element 60 are of such dimension that, when assembled together, they will fit snugly within the pocket formed by the walls 52 and 53 of the case 51. The aperture 64 in the nose block 59 has a diameter slightly larger than the outside diameter of the sleeve 71 of the snap fastener male element 57, and the protuberances 65 of the nose block 59 are spaced from each other a distance somewhat less than the diameter of the sleeve 71. Since the nose block is formed of resilient material, it may be detachably secured within the case 51 to the male element 57 by forcing the protuberance 65 over sleeve 71 adjacent flange 70 so that the sleeve is engaged in the aperture 64, as shown in Fig. 9. During normal use of the case 51, the protuberances 65 will prevent dislodgment of the nose block 59 from the sleeve 71. Since the nose block 59 snugly engages the groove 67 of the spacer element 60 when the latter is inserted in the case 51, the nose block 59, when detachably secured to sleeve 71, acts to prevent dislodgment of spacer element 60 during normal use of case 51.

The spectacles are inserted in case 51 with the lenses 26 facing rearwardly thereof and with the nose bridge 27 resting on the nose block 59. The temples 25 are folded over the back of the lenses and are retained within the pocket of the case 51, thus spacing the lenses from the front wall 52 thereof. With the spectacles thus supported, the spacer element 60 contacts the nose bridge 27 and acts to space the lenses 26 from the rear wall 53 of the case 51. Thus, the lenses 26 are suspended intermediate of and free of contact with the walls 52 and 53.

In Figs. 12, 13 and 14 there is shown a modified form of lens spacer element 60' for use in connection with nose block 59 in case 51. The spacer element 60' comprises a pair of spaced block-like components 74 and 75 inte-

grally joined by a flexible connector 76. The spacer component 75 has a U-shaped groove 67 formed in its inner face into which the rear portion of the nose block 59 is snugly engaged, as shown in Fig. 14. The spacer component 74 has a U-shaped recess 77 formed therein in the bottom of which is a centrally disposed opening 78 of keyhole-like configuration having a circular aperture 79 at the top thereof. The opening 78 in spacer element 60' is of such configuration and is so located as to be congruent with the opening 63 in nose block 59 when the nose block and spacer element 60' are properly assembled, as shown in Fig. 13. As is clearly shown in Fig. 13, the distal ends of the opposing legs of the nose block 59 rest upon the connector 76 when the nose block and spacer element 60' are assembled.

The assembled nose block 59 and spaced element 60' are detachably secured within the pocket of case 51 by snapping their congruent apertures 79 and 64 onto the sleeve 71 of the snap fastener male element 57, as shown in Fig. 14. With the spacer element 60', it is immaterial whether the lenses 26 of the spectacles face rearwardly or forwardly of case 51 for in either event the spacer components 74 and 75 serve to space the lenses from the case walls 52 and 53. It is to be noted that in Fig. 14 the lenses 26 face forwardly of the case 51.

If desired, the nose block 59 and spacer element 60' may be formed as an integral unit, as shown in Fig. 15. In such event, there is no need for the opening 63 in the nose block and hence its front wall 62 may be eliminated. The integral unit of Fig. 15 will be effectively retained within the pocket of case 51 by snapping the aperture 79 of the spacer element 60' onto the sleeve 71 of the snap fastener male element 57.

Referring next to Fig. 16, where the outline of a spectacle case is indicated in dot and dash lines, and also to Fig. 17, there is disclosed a further embodiment of this invention. More particularly, there is shown a unitary nose block and lens spacer element having spaced upstanding front and rear spacer components 80 and 81 integrally joined at their bottoms to a support 82 for the nose bridge 27 of a pair of spectacles. Disposed at the bottom of support 82, in T-shaped relation thereto, is an elongated block 83 having generally U-shaped indentations 84 formed in the opposite ends thereof. The block 83 either may be integrally joined to support 82 or may be a separate element secured thereto by an appropriate adhesive.

With a pair of folded spectacles resting on support 82 intermediate of spacer components 80 and 81, the lower portions of the frames of the lenses 26 are disposed, respectively, within the indentations 84 and hence are retained thereby against pivotal forward or rearward displacement about support 82. Thus, the spacer components 80 and 81 and the indentations 84 cooperate to prevent the spectacle lenses 26 from coming into contact with the inside walls of the spectacle case. Preferably, the unitary nose block and lens spacer element of Figs. 16 and 17 is formed of plastic and is secured within the spectacle case by means of an adhesive indicated at 86 in Fig. 17.

With the unitary nose block and lens spacer element of Figs. 16 and 17, it is immaterial whether the spectacles are inserted in the case with their lenses facing rearwardly or forwardly, for in either event they are sustained free of contact with the case walls. It is to be noted that in Fig. 16 the spectacle lenses face rearwardly of the case, whereas in Fig. 17 they face forwardly thereof.

In Figs. 18 and 19 there is shown still another embodiment of this invention, the same comprising a unitary nose block and lens spacer element having spaced front and rear spacer components 88 and 89 joined at their bottoms by a support 90 for the nose bridge 27 of a pair of spectacles. The spacer components 88 and 89 are supported at their upper ends upon spaced front and

rear walls 91 and 92 which, as shown in Fig. 19, are in contiguous relation with the walls of the spectacle case when inserted in the pocket thereof. Dependent from the front wall 91, at each end thereof, are legs 93, each 5 of which is paired in spaced relation with a corresponding leg 94 dependent from rear wall 92. Each pair of legs 93 and 94 sustain a laterally extending elongated channel 95 having a groove 96 in the bottom thereof. The grooves 96 in the channels 95 support the lower 10 portions of the frames of the spectacle lenses 26 and at the same time prevent their pivotal displacement about support 90. Thus, the spacer components 88 and 89 and the channels 95 cooperate to prevent the spectacle lenses 26 from coming into contact both with the spacer 15 component supporting walls 91 and 92 and with the walls of the pocket of the spectacle case.

The unitary nose block and lens spacer element of Figs. 18 and 19 preferably is formed of metal blanked from suitable sheet stock and enveloped within a covering 20 of soft textile, leather or plastic material, or is formed of rigid injection molded plastic, such as styrene or the like. The front wall 91 is formed with a keyhole-like opening 98 which is adapted to be detachably secured to the sleeve 71 of the snap fastener male element 57 to 25 retain the unit within the pocket of the spectacle case.

With the unitary nose block and lens spacer element of Figs. 18 and 19, it is immaterial whether the spectacles are inserted in the case with their lenses facing rearwardly or forwardly, for in either event they are sustained free 30 of contact with the walls of the case. It is to be noted that in Fig. 18 the spectacle lenses face rearwardly of the case, whereas in Fig. 19 they face forwardly thereof.

In Figs. 20 and 21 there is shown the adaptation of this invention to another type of spectacle case 101 having 35 a rear wall 102, an abbreviated front wall 103, end walls 104 and a closure flap 105. The case 101 preferably is made of rigid material, such as sheet metal, and has an inside lining of soft, flexible material and an outside covering of somewhat sturdier material. Disposed centrally of the inner surface of the rear wall 102 is a lens spacer element 106 which is adapted to space the lenses 26 of the spectacles from the wall 102. The spacer element may be a separate element adhesively secured to the wall 102 or may comprise an integral boss formed in the wall 102 by press stamping.

45 The lenses 26 are spaced from the flap 105 by the folded temples 25, which are retained within the case 101. If desired, a lens spacer element similar to the spacer element 106 may be centrally disposed of the inner surface of the flap 105, in which event the spectacles may be placed in the case 101 with their lenses 26 disposed either forwardly or rearwardly thereof.

50 While preferred embodiments of this invention have been described in detail, it will be obvious to one skilled in the art that various modifications may be made therein without departing from the invention as hereinafter claimed.

Having thus described our invention, we claim:

55 1. A spectacle case having opposing walls disposed in spaced relation; means whereby said walls are joined together at their opposing ends; spectacle support means mounted internally of the case and sustained on at least one of said walls; a spacer element mounted internally of the case and sustained on at least one of said walls 60 for spacing the spectacle lenses from the case walls; and means whereby the spacer element and the support means are detachably secured to each other.

65 2. A spectacle case according to claim 1 wherein the support means comprises a nose block adapted to engage the nose bridge of the spectacles.

70 3. A spectacle case having a pocket formed by opposing case walls; a rigid cup-like liner disposed within the pocket, said liner comprising detachable opposing portions complementally configured to retain a pair of spectacles therebetween; means for detachably securing said

liner portions in opposing relationship; spectacle support means mounted internally of the liner and supported on one of said liner portions; a spacer element mounted internally of the liner and supported on one of said liner portions for spacing the spectacle lenses intermediate the liner portions; and means for detachably securing the spacer element to the spectacle support means.

4. In a spectacle case, a rigid cup-like liner, said liner comprising separate opposing portions complementally configured to retain a pair of spectacles therebetween; means for detachably securing said liner portions in opposing relationship; spectacle support means mounted internally of the liner and supported on one of the said liner portions; a spacer element mounted internally of the liner and supported on one of said liner portions for

spacing the spectacle lenses intermediate of said liner portions; and means for detachably securing the spacer element and the spectacle support means together.
